UNITED STATES PATENT OFFICE.

ALFRED SMALLWOOD, OF LONDON, ENGLAND.

FURNACE.

1,335,204.

Specification of Letters Patent. Patented Mar. 30, 1920.

Application filed July 31, 1918. Serial No. 247,644.

To all whom it may concern:

Be it known that I, ALFRED SMALLWOOD, a subject of the King of Great Britain, residing at 42 Hargrave Park, Highgate, London, N., in the county of Middlesex, England, metallurgist, have invented certain Improvements in or Relating to Furnaces, of which the following is a specification.

This invention comprises certain improvements in or relating to furnaces.

According to the present invention, air for combustion is adapted to be heated in a recuperator system advantageously located in the crown or roof of the furnace, said air being afterward passed into longitudinal flues advantageously in the side walls of the furnace, which flues communicate by ports with the goods chamber at intervals along the length thereof, said ports being located in relation to other ports which admit the heating gases. The ports for admitting the air and heating gases may be individually regulable.

In order that this invention may be clearly understood and readily carried into practice, reference may be had to the appended explanatory sheets of drawings, upon which:

Figure 1 is a sectional side elevation of a furnace according to the present invention, the plane of section being on line 1—2 of Fig. 2.

Fig. 2 is a sectional end elevation of the furnace shown in Fig. 1.

Fig. 3 is a sectional plan of the furnace shown in Figs. 1 and 2, the plane of section being on line 3—4 of the figure last mentioned.

Fig. 4 is a sectional plan of the furnace shown in Figs. 1 and 2, the plane of section being on line 5—6 of the figure last mentioned.

Fig. 5 is a section on the line 7—8 of Fig. 3.

In a convenient embodiment of the present invention, the goods are adapted to be supported upon a truck *a* within the body of which two longitudinal combustion chambers *b* are provided to the center extending substantially the full length of the truck body. Into the extremity of these combustion chambers, Bunsen burners *c* are adapted to project. The other extremities of the combustion chambers communicate by way of laterally extending passages *d* with heat flues *e* also extending throughout a

substantial part of the length of the furnace so that the gases are enabled to flow in a reverse direction along the heat flues, said heat flues occurring one on each side of the truck body. From these heat flues at intervals along their length, lateral ports *f* extend which communicate with the goods chamber *g*, which lateral ports may be individually regulable by dampers *h*. In the vicinity of these ports secondary heated air is adapted to be admitted. Said secondary air is admitted by way of ports *i* located at intervals along the length of the furnace, said ports extending from longitudinal hot air flues *j* in the side walls of the furnace. Said ports *i* may be individually regulable, as for instance by dampers *i*¹. The secondary air before passing into said flues in the side walls of the furnace is adapted to pass through a recuperator system in the roof of the furnace. In one arrangement five longitudinal flues *k* are provided through which the waste gases are adapted to pass, these flues being spaced at intervals across the width of the furnace. The gases from the goods chamber *g* egress by way of a flue *l* which communicates with a jacket space *m*. At the other end of the furnace this jacket space *m* is in communication with the flues *k* by openings *n*. At the front end of the furnace the flues *k* communicate by openings *o* with the stack *p*. On each side of the upper part of the furnace and in the horizontal plane of the flues *k* an air flue *q* is provided which extends three times the length of the furnace in S form and afterward extends downwardly at *r* to the longitudinal air flue *j* in the side wall of the furnace which communicates by the ports *i* with the goods chamber in the vicinity of the ports *f* by which the primarily ignited fuel issues. The air may enter the flue *q* by an opening *s* in the side wall of the furnace, which opening *s* offers admission for atmospheric air to an upwardly extending flue *t* which communicates with a transverse flue *u* leading to the flue *q*. Primary air may be admitted in the vicinity of the burner from a broad shallow flue *v* located in the truck body below the combustion chamber and heat flue. The air is adapted to enter this flue at *w* and at the opposite end of the furnace said flue *v* communicates by an upward flue *x* with a port *y* which admits to the combustion chamber *b* in the vicinity of the burner *c*.

What I claim as my invention and desire to secure by Letters Patent is:—

1. In a furnace, in combination with a combustion chamber and a goods chamber 5 interconnected by a series of ports, means for introducing air into said combustion chamber to effect partial combustion of the fuel gases, a recuperating system located in the crown or roof of the furnace, hot air 10 flues, air ducts in said system communicating with said hot air flues, said flues extending horizontally substantially the length of the furnace side walls and being provided with distributed ports contiguous to said first named ports.
- 15 2. In a furnace, a carriage, longitudinal heat flues located in the carriage body, a goods chamber communicating with said heat flues by a series of ports, means for introducing partially combusted fuel gases into said heat flues, a recuperating system, and means terminating in a series of ports contiguous to said first named ports for conducting air through said system to preheat and distribute the air so as to effect complete combustion of the fuel gases.
- 20 3. In a furnace, a carriage, longitudinal combustion chambers in the carriage body, longitudinal hot air flues in said carriage body communicating with said combustion chambers, a goods chamber communicating with said hot air flues by a series of ports, means for introducing partially combusted fuel gases into said heat flues, a recuperating system, and means for conducting air through said recuperating system and dis-

charging the air through a series of ports contiguous to said first named ports.

4. In a furnace, a carriage, longitudinal combustion chambers in the carriage body, longitudinal hot air flues in said carriage body communicating with said combustion chambers, a goods chamber communicating with said hot air flues by a series of ports, means for introducing partially combusted fuel gases into said heat flues, a recuperating system, longitudinal heat flues in the furnace walls, and air ducts in said system communicating with said heat flues, said heat flues having a plurality of ports contiguous to said first named ports.

- 45 5. In a furnace, a carriage, longitudinal combustion chambers in the carriage body, longitudinal hot air flues in said carriage body communicating with said combustion chamber, a goods chamber communicating with said hot air flues by a series of individually regulable ports, means for introducing partially combusted fuel gases into said heat flues, a recuperating system, longitudinal heat flues in the furnace walls, and air ducts in said system communicating with said heat flues, said heat flues having a plurality of individually regulable ports contiguous to said first named ports.

In witness whereof I have hereunto set my hand in the presence of two witnesses.

ALFRED SMALLWOOD.
